Robert L. Bailey, Spokane, Wash., assignor, by mesne assignments, to National Distillers and Chemical Corporation, a corporation of Virginia

Filed June 8, 1964, Ser. No. 80,328

Term of patent 14 years

(Cl. D58—5)

Fig. 1

Fig. 2

Fig. 3

FIG. 1 is a side elevation of a jug embodying my new design;

FIG. 2 is a side view taken from the right in FIG. 1; and

FIG. 3 is a top view thereof.

The dominant features of the design are shown in full lines in the drawings.

This application is a continuation-in-part of my co-pending application Serial No. D. 72,762, filed December 7, 1962, now abandoned.

I claim:

The ornamental design for the jug, as shown and described.
